MOTION PICTURE MACHINE

Albert S. Howell, Chicago, Ill., assignor to The
Bell & Howell Company, Chicago, Ill., a cor-
poration of Illinois

Application February 12, 1931, Serial No. 515,246

12 Claims. (Cl. 88—18)

My invention relates particularly to motion picture projecting machines although not limited to this use alone.

Generally speaking the invention has for its object the simplification of the operation of motion picture machines, particularly with reference to motion picture projection machines, and particularly with reference to lacing of the motion picture film in the machine and the control of the machine in the event of abnormal shortening of the compensating loops of the film between the intermittent and constant film feed devices of the machine or breakage or termination of the film.

With this object in view my invention consists in certain features of novelty in the construction, combination and arrangement of parts by which the said object and certain other objects, herein-after appearing, are attained, all as fully described with reference to the accompanying drawings and more particularly pointed out in the appended claims.

In the said drawings:—

Figure 1 is a side elevation of a motion picture projecting machine embodying my invention;

Figure 2 is a partial opposite side elevation of the same with parts broken away and shown in section;

Figure 3 is a partial front elevation of the same;

Figure 4 is a partial side elevation similar to Figure 1 with parts broken away and shown in section and showing parts in different positions than those in which they are shown in Figure 1;

Figure 5 is a partial side elevation similar to Figure 2 with parts broken away and shown in section and showing parts in different positions than those in which they are shown in Figure 2;

Figure 6 is a partial sectional view substantially on the line 6—6 of Figure 5;

Figure 7 is a partial section on the line 7—7 of Figure 6; and

Figure 8 is a partial section on the line 8—8 of Figure 3.

Like characters of reference indicate like parts in the several views.

Referring to the drawings, 1 designates the body of the machine which is inclusive of a forward frame 2 disposed in a vertical rearwardly and forwardly extending plane. Slidably mounted, as designated at 3, on one side of the frame 2 for rearward and forward movement is a lens mount member 4 which is inclusive of a forwardly disposed rearwardly and forwardly extending bored portion 5 in which a projection lens, not shown, is adjustably mounted. See Figures 1, 3 and 4.

Disposed at the rear of the lens mount member 4 is an apertured intermittent feed film guide which is inclusive of a rear face guide member 6 and a front face guide member 7 carried on the rear end of the lens mount member 4 for face-wise movement therewith into and out of film retaining relation with the face guide member 6. The intermediate portion of the guide is apertured, as designated at 8, in alignment with the lens mount member 4 for cooperation of a film 9 in the guide with a lens in the lens mount member in the projection of pictures from the film, projection light being derived from a suitable source, such as an incandescent electric lamp 11 enclosed within the body 1 at the rear of the 15 guide. See Figures 1, 3 and 4.

Sliding movement of the lens mount member 4 is controlled by a forwardly disposed manually operated lever 12 pivotally mounted on the frame 2, as designated at 13, and provided with a pivoted crank block 14 slidably engaging a vertical slot 15 on the lens mount member.

Arranged, one above and one below the lens mount member 4, are two constant feed sprockets 16 which feed the film 9 to and from the ends 25 of the intermittent film feed guide in timed relation with the intermittent film feed mechanism, not shown, which intermittently feeds the film in the guide, the film being looped between the sprockets and the ends of the guide, as shown 30 in Figure 1, to compensate for the intermittent feed of the film in the guide and the constant feed of the film by the sprockets.

Mounted for independent movement in a vertical slide 17 on the frame 2 immediately inward 35 of the lens mount member 4, are two plates 18 which carry film retaining devices 19 movable with the plates 18 into and out of film retaining relation with the sprockets 16. See Figures 1 and 4.

Movement of these film retaining devices is controlled by the lever 12 and they are moved into and out of film retaining relation with the sprockets 16 with corresponding movement of the lens mount member 4 and the face guide 45 member 7 by means of an inwardly projecting stud 21 on the lens mount member and slidably engaging in transverse cam slots 22 in the plates 18, see Figure 4, in a manner fully described and claimed in U. S. Letters Patent #1,624,730 granted 50 April 12, 1927 for Motion picture apparatus on application of Albert S. Howell. Figure 1 shows the position of the parts with the film retaining devices 19 and the face guide member 7 in film retaining position with the film laced therein for 55

the operation of the machine and Figure 4 shows the position of the parts with the film retaining devices 19 and the face guide member 7 out of film retaining position for the lacing and unlacing of the film.

Arranged, one above and one below the lens mount member 4, at the front of the frame 2 are two transverse shafts 23 which extend through and are pivotally engaged in bores 10 through the frame. See Figure 3.

Secured on the ends of the shafts 23 adjacent the sprockets 16 are two arms 24 which extend rearwardly from the shafts and have film engaging rollers 25 mounted on their rear ends, 15 these rollers lying within the film loops between the sprockets 16 and the intermittent film feed guide for engagement therewith. See Figures 1, 3 and 4.

Secured on the opposite ends of the shafts 23 20 are two arms 26 which extend toward each other and have their free ends pivotally and slidably engaged with each other, as designated at 27, whereby the arms 24 are connected for movement together in opposite directions to simultaneously 25 engage the aforementioned film loops and to disengage therefrom. See Figures 2 and 5. A spring plunger device 28 on the frame 2 engages the upper arm 26 to yieldably urge the arms 24 to their inner positions disengaged from the 30 aforementioned film loops as shown in Figure 1.

Pivoted mounted on the upper shaft 23 between the upper arm 24 and the frame 2 is an arm 29 which extends downwardly therefrom and has its lower end engaged with a cam formation 31 on the lever 12 for actuation of the arm 29 with movement of the lever 12.

The upper arm 24 is provided with an extension arm 32 projecting downwardly from the upper shaft 23 and overlying the arm 29, and a 40 stud 33 on the lower end of the extension arm 32 engages in a relatively large aperture 34 in the arm 29 to form a lost motion connection therebetween. See Figures 1, 3, 4 and 8.

A torsion spring 35 encircles the upper shaft 23 45 adjacent the arm 29 and lies within an enlargement of the bore of the frame 2 in which this shaft is engaged, and has one end angularly secured with this shaft and the other end angularly secured with the arm 29, and yieldably urges the arms 24 in the direction of their outer positions with reference to arm 29, the spring 35 being stronger than the spring device 28 so that normally the arms 24 are positioned in their outermost position with reference to the arm 29, which 50 position is determined by engagement of the stud 33 against the corresponding side of the aperture 34. See Figures 1, 3, and 8.

The arms 24 can be moved, against the influence of the spring 35, a limited extent in the 60 direction of their inward position, that is until the stud 33 engages against the opposite side of the aperture 34.

The spring device 28 yieldably urges the arms 24 and arm 29 in the direction to maintain the 65 arm 29 in engagement with the cam formation 31 on the lever 12, so that this lever controls the position of the arms 24 in addition to controlling the position of the lens mount member 4, the front face guide 7 and the retaining devices 19.

The arrangement is such that, in the position of the lever 12 as shown in Figure 1, the face guide member 7 and the retaining devices 19 are in their film retaining positions for operation of the machine, and the arms 24 in their inward 70 positions with the film engaging rollers 25 spaced

inwardly from the loops of the film 8 between the sprockets 16 and the intermittent film feed guide.

When the lever 12 is in the opposite position of its movement, as shown in Figure 4, the face guide member 7 and the retaining devices 19 are out of their film retaining positions for the lacing and unlacing of the film, and the arms 24 and the film engaging rollers 25 are disposed in their outer or film loop forming positions, that is in the positions where the rollers 25 engage the film to form predetermined loops thereof between the sprockets 16 and the intermittent film feed guide, with obvious convenience in lacing of the film.

In the lacing of the film, the face guide member 7 and the retaining devices 19 are out of film retaining position and the arms 24 and the rollers 25 are in their outer or loop forming positions as shown in Figure 4. The film is then laced on one sprocket and is then trained over the rollers 25 and then engaged on the other sprocket, the film being tensioned against the spring 35 to engage the perforations of the film on the teeth of the second sprocket.

Then the lever 12 is operated to move the face guide member 7 and the retaining devices 19 into film retaining position as shown in Figure 1, the arms 24 and the rollers 25 being moved to their inner positions during this operation by means of the cam formation 31.

The mechanism of the machine is driven from an electric motor 36 through a releasable clutch 37, see Figure 2, and the clutch is controlled as follows.

A lever 38 is arranged on the side of the frame 35 on which the arms 26 are arranged and is pivoted on the frame, as designated at 39. See Figures 2 and 5. This lever 38 is connected with the clutch 37 for controlling it, as designated at 41, and is yieldably urged into clutch released 40 position, as shown in Figure 5, by means of a spring plunger device 42.

Pivoted on the lower shaft 23 for movement independently thereof is a latch lever 43 arranged alongside the lower arm 26, and this latch lever 45 is provided with a latch formation 44 adapted to engage a cooperating latch formation 45 on the lever 38 to maintain the lever 38 in clutch engaged position, as shown in Figure 2, against the influence of the spring device 42, release of 50 the latch lever permitting the spring device 42 to operate the lever 38 to clutch released position as shown in Figure 5.

A spring 46 yieldably urges the latch lever 43 into engaged position so that it automatically 55 locks the lever 38 in clutch engaged position as the lever 38 is moved into such position.

A manually actuated lever 47 is pivotally mounted intermediately, as designated at 48, on the lever 38 adjacent its upper end, movement 60 of the lever 47 with reference to the lever 38 being limited by stop pins 49 on the lever 38.

Forward movement of the lever 47 from the position shown in Figure 5 causes forward movement of the lever 38 to engage the clutch 37 by 65 reason of the engagement of the lever 47 with the lower stop pin 49, the latch lever 43 automatically locking the lever 38 in clutch engaged position as shown in Figure 2.

Rearward movement of the lever 47 from the position shown in Figure 2 causes pivotal movement of this lever with reference to the lever 38 to cause the lower end of the lever 47 engaging the latch lever 43, as designated at 51 in Figure 2, to move the latch lever and release the lever 75

28 therefrom, whereupon the spring device 42 actuates the lever 38 rearwardly to release the clutch 37.

Thus, is the clutch 37 manually controlled to start and stop operation of the machine.

Secured on the latch lever 43 is a pin 52 which is engaged for movement in an angularly arranged slot 53 in the lower arm 26, so that movement of the arms 24 inwardly from their normal inward position effects movement of the latch lever 43 to release the lever 38 to release the clutch 37 to stop operation of the machine, this movement being effected by engagement of one end of the slot 53 with the pin 52. Movement 10 of the pin 52 in the slot 53 permits movement of the latch lever into released position independently of the arms 24 and permits movement of the arms 24 to their outer or loop forming position independently of the latch lever.

20 As a result of the operative connection between the lower arm 26 and the latch lever 43 movement of the arms 24 inwardly from their normal inward position causes release of the latch lever 43 from the lever 38 and consequent release of the clutch 37 and stoppage of the machine.

Accordingly, if either loop of the film between the intermittent feed guide and the sprockets 16 becomes abnormally shortened as by failure of the feed of the film in the intermittent feed 30 guide, the corresponding roller 25 is engaged by the abnormally shortened loop and moved inwardly with resultant stopping of the machine.

In such case, the lever 42 is moved to film released position, causing the film loops to be reformed by the movement of the rollers 25 to their outer or loop forming position, after which the lever 42 is returned to film retaining position and the machine is started by forward manual movement of the lever 47 to engage the clutch.

40 The lower roller 25 functions to stop operation of the machine when the end of the film is reached by reason of the fact that the end of the film becomes stationary in the guide after it passes out of the range of the intermittent feed 45 mechanism, not shown, operative on the film in the guide, with resultant shortening of the lower film loop by feeding of the film by the lower sprocket 16.

Referring to Figure 6, a lever 54 is pivotally 50 mounted within the body 1, as designated at 58, and the lower end of this lever is provided with a safety shutter or screen 56 in the form of a frosted glass mounted in a frame 57 on the lever, as shown in Figures 6 and 7.

55 In the pivotal movement of the lever 54, the shutter 56 is movable from a position intercepting the projection light between the lamp 11 and the aperture 8 of the intermittent film feed guide for reducing the intensity of the light on the film, see Figure 6, to a position out of the path of the projection light is indicated by broken lines in Figure 6.

The lever 54 is urged in the direction of its projection light in intercepting position by a 60 spring 58, and a transversely extending rod 59 slidably mounted within the frame 2 engages the lever 54, as designated at 61, for operating the lever out of projection light intercepting position.

70 A spring device 62 operates on the slide rod 59 to actuate the lever 54 into projection light intercepting position, this spring device being stronger than the spring 58 and the spring 58 acting to cause the lever 54 to follow the movement of the rod 59 and to permit manual opera-

tion of the lever 54 out of projection light intercepting position independently of the rod 59 by the manipulation of the upper end of the lever which projects upwardly through an opening in the frame 2 for this purpose, as designated at 63.

The end of the slide rod 59 adjacent the lever 38 extends through and is slidably engaged in a bore through the frame 2 and is so disposed that when the lever 38 is in clutch released position, as shown in Figure 5, a cam formation 64 on the upper end of this lever overlies the adjacent end of the rod, and when the lever 38 is in clutch engaged position, as shown in Figure 2, the cam formation is spaced forwardly of the rod.

Thus, when the lever 38 is in clutch engaged position, the spring device 62 maintains the lever 54 and shutter 56 out of projection light intercepting position for the operation of the machine. When the lever 38 is moved to clutch 20 released position to stop operation of the machine, the cam formation 64 engages the adjacent end of the rod 59 and moves the same to position the lever 54 and shutter 56 in light intercepting position to prevent damage to the 23 film.

Accordingly, stoppage of the machine either by hand or automatically by abnormal shortening of the compensating film loops causes the safety shutter to function.

30 While I have described and shown the preferred embodiment of my invention I do not wish to be limited to the precise details of construction as changes may readily be made without departing from the spirit of my invention, but having thus described my invention, I claim as new and desire to secure by Letters Patent the following:

1. In a motion picture machine the combination with a film engaging member movable into position to form a compensating film loop and into another position to be engaged and moved by the film upon abnormal shortening of said loop, of means for predeterminedly positioning said film engaging member in either of said positions, and means under the control of said film engaging member and adapted to stop operation of the machine upon movement of said film engaging member by said film from said second mentioned position.

2. In a motion picture machine the combination with a film engaging member movable into position forming a predetermined compensating film loop and into another position to be engaged and moved by the film upon abnormal shortening of said loop, of means for predeterminedly positioning said film engaging member in either of said positions, a releasable driving clutch for operating the machine, and means under the control of said film engaging member and adapted to release said clutch upon movement of said film engaging member by said film from said second mentioned position.

3. In a motion picture machine the combination with a film engaging member mounted on the machine for movement into position forming a predetermined compensating film loop and into another position to be engaged and moved by the film upon abnormal shortening of said loop, of means for predeterminedly positioning said film engaging member in either of said positions, a releasable driving clutch for operating the machine and yieldably urged into released position, a releasable latch for maintaining said clutch in engaged position, and a connection between said latch and said film engaging member whereby

movement of said film engaging member by said film from said second mentioned position releases said latch.

4. In a motion picture machine the combination with a film engaging member mounted on the machine for movement into position forming a predetermined compensating film loop and into another position to be engaged and moved by the film upon abnormal shortening of said loop, 10 of means for predeterminately positioning said film engaging member in either of said positions, a releasable driving clutch for operating the machine and yieldably urged into released position, a releasable latch yieldably urged into position for 15 maintaining said clutch engaged, a manually operable member operable in one direction for releasing said clutch to release said clutch and in the opposite direction to engage said clutch and engage said latch to maintain the clutch engaged, 20 and a connection between said latch and said film engaging member for releasing said latch to release said clutch upon movement of said film engaging member by said film from said second mentioned position.

25. 5. In a motion picture machine the combination with an intermittent film feed guide and constant film feed sprocket means for feeding a film to and from said guide, of two film loop forming members movable into position to form compensating 30 film loops between said guide and said constant film feed means and into other positions to be engaged and moved by the film upon abnormal shortening of the corresponding loop, means whereby said loop forming members are predeterminately positioned together in either of said 35 positions, and means whereby operation of the machine is stopped upon movement of one of said loop forming members by said film from its second mentioned position.

40. 6. In a motion picture machine the combination with an intermittent film feed guide and constant film feed sprocket means for feeding a film to and from said guide, of film loop forming members movable into position to form compensating film loops between said guide and constant film feed means and into other positions to be engaged and moved by the film upon abnormal shortening of the corresponding loop, means whereby said loop forming members are predeterminately positioned together in either of said 45 positions, means for stopping operation of the machine and yieldably urged into stopping position, a releasable latch for maintaining said last mentioned means in position for operation of the machine, and means whereby movement of one of said loop forming members by said film out of its second mentioned position releases said latch.

60. 7. In a motion picture machine the combination with an intermittent feed film guide and a cooperating constant film feed sprocket device one of which is inclusive of a film retaining member movable into and out of film retaining position, of a film loop forming member movable into position to form a compensating film loop between said guide and said sprocket device and into a second position to be engaged and moved by the film upon abnormal shortening of said loop, means whereby said loop forming member is predeterminately positioned in loop forming 65 position with movement of said retaining member out of retaining position and in said second position with movement of said retaining member into retaining position, and means under the control of said loop forming member and adapted 70 to stop operation of the machine upon movement 75

of said loop forming member by the film from said second position.

8. In a motion picture machine the combination with an intermittent feed film guide and a cooperating constant film feed sprocket device 5 each of which is inclusive of a film retaining member movable into and out of film retaining position, of a film loop forming member movable into position to form a compensating film loop between said guide and said sprocket device and into a second position to be engaged and moved by the film upon abnormal shortening of said loop, means whereby said retaining members are operated together into and out of retaining position, means whereby said loop forming member is predeterminately positioned in loop forming position with movement of said retaining members out of retaining position and in said second position with movement of said retaining members into retaining position, means controlling operation of the machine and yieldably urged into position to stop operation of the machine, a releasable latch for maintaining said controlling means in position to operate the machine, and means whereby movement of said loop forming member 10 by said film out of said second position releases said latch.

9. In a motion picture machine the combination with an intermittent feed film guide and a cooperating constant film feed sprocket device 30 each of which is inclusive of a film retaining member movable into and out of film retaining position, of a film loop forming member movable into position to form a compensating film loop between said guide and said sprocket device and 35 into a second position to be engaged and moved by the film upon abnormal shortening of said loop, means whereby said retaining members are operated together into and out of retaining position, means whereby said loop forming member is predeterminately positioned in loop forming position with movement of said retaining members out of retaining position and in said second position with movement of said retaining members into retaining position, a releasable clutch for 40 operating the machine and yieldably urged into released position, a releasable latch yieldably urged into position for maintaining said clutch engaged, a manually operable member operable in one direction for releasing said latch to release 45 said clutch and in the opposite direction to engage said clutch and engage said latch to maintain the clutch engaged, and a connection between said latch and said loop forming member for releasing said latch to release said clutch upon 50 movement of said loop forming member by said film from said second position.

10. In a motion picture machine the combination with a compensating film loop forming member mounted on the machine for movement into 60 position to form a loop and out of such position in a direction inwardly of said loop, means yieldably urging said forming member out of said position, an actuating member, a lost motion operating connection between said forming member and 65 said actuating member, a cam member operative upon said actuating member to operate said forming member into said position, and means yieldably urging said forming member in the direction of said position with reference to said actuating member and overcoming the influence of said first mentioned yieldably urging means.

11. In a motion picture machine the combination with a pivotally mounted compensating film loop forming member mounted on the machine 75

for movement into position to form a loop and out of such position in a direction inwardly of said loop, spring means yieldably urging said forming member out of said position, an actuating member pivotally mounted coaxially with said forming member, a lost motion operating connection between said forming member and said actuating member, a pivotally mounted cam member operative upon said actuating member to operate said forming member into said position, and spring means operative between said forming member and said actuating member and urging said forming member in the direction of said position and overcoming the influence of said first mentioned spring means.

12. In a motion picture projecting machine the combination of a releasable clutch for operating

the machine and yieldably urged into released position, a safety shutter movable to a position disposed across the path of projection light to a film in the machine and yieldably urged into said position, a releasable latch yieldably urged into position for maintaining said clutch engaged and said shutter in operative position, a manually operable member operable in one direction for releasing said latch to release said clutch and render said shutter operative and in the opposite direction to engage said clutch and render said shutter inoperative and engage said latch to maintain the clutch engaged and said shutter inoperative, and means under the control of said film for releasing said latch.
